UNITED STATES PATENT OFFICE

JOHN HAYS HAMMOND, JR., OF GLOUCESTER, MASSACHUSETTS

SOUNDING BOARD

Original application filed June 6, 1929, Serial No. 370,484. Divided and this application filed July 21, 1930, Serial No. 469,518. Renewed June 8, 1932.

This invention relates to musical instruments of the percussive type, and more particularly to a piano having sound propagating and reenforcing means associated therewith.

This application is a division of my copending application Serial No. 370,484 filed June 13, 1929, for piano with reaction loud speaker.

In accordance with the present invention 10 a sound propagating device, such as a loud speaker which is capable of converting electrical vibrations into compressional waves, is applied to a portion of the sounding board of a piano which is substantially inactive for 15 each of the notes of the musical scale. The arrangement is such that the loud speaker may be utilized for the reproduction of programs without interfering with the operation of the piano or the reenforcing qualities of 20 the sounding board.

A feature of the invention is a sounding board, a portion of which is mounted in cantilever relationship to the frame of the piano and is free to vibrate at its outer edges.

25 A further feature of the invention is a sounding board having a loud speaker or other device mounted on a cantilever portion so as not to interfere with the normal action of the remaining portion of the sounding board.

The invention also consists in certain new and original features of construction and combinations of parts hereinafter set forth and claimed.

35 Although the novel features which are believed to be characteristic of this invention will be particularly pointed out in the claims appended hereto, the invention itself, as to its objects and advantages, the mode of its 40 operation and the manner of its organization may be better understood by referring to the following description taken in connection with the accompanying drawing forming a part thereof, in which

45 Fig. 1 is a top plan view of a piano showing the arrangement of the sounding board and loud speaker.

In the following description and in the 50 claims parts will be identified by specific names for convenience, but they are intended

to be as generic in their application to similar parts as the art will permit.

Referring to the drawing more in detail, the invention is shown as applied to a grand piano 10 having the usual keyboard 11 and 55 sounding board 13. Above the sounding board 13 is mounted a metallic frame 14 on which the strings are mounted in the usual manner. Said strings are supported from bridges 15 and 16 which are secured to the 60 sounding board of the piano.

Sounding board 13 is supported at its periphery from the frame 25 of the piano, and is provided with a circular opening 20 below which is mounted a loud speaker 21, or other 65 sound propagating device. Said speaker may be clamped to a retaining ring 22 and secured by bolts 23, or may be attached to the sounding board in any other convenient manner. A diagonal supporting brace 37 is se- 70 cured to the piano and carries a portion of the sounding board. Said brace preferably forms a triangle with the sides of the piano in which the loud speaker 20 is mounted. Slots 40 are formed in the sounding board 75 adjacent the corner of the piano and between said corner and brace 37 so that the portion of the sounding board supporting the loud speaker is held in cantilever relationship to the frame of the piano, and is free to vibrate 80 at its extremities.

In accordance with the above arrangement, the compressional waves produced by the loud speaker device 21 are applied to the sounding board and cause the same to vibrate and 85 reenforce said waves. The cantilever portion of the sounding board which is free to vibrate as a unit permits the waves to be amplified without distortion, and materially assists in permitting the desired vibrations to be set 90 up in the entire sounding board. Furthermore, the provision of a cantilever section of the sounding board permits the same to vibrate more readily when the piano is played in the usual manner, and assists in securing 95 the proper tone quality.

It is obvious that the loud speaking device may be utilized either in connection with a radio receiver or in connection with the piano itself. It is preferably located at a nodal point 100

on the sounding board so that the normal operation thereof will not be interfered with in playing a selection on the piano.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. In a piano, a sounding board, a diagonal brace extending across a corner of said sounding board, said corner being free from support other than said brace.
2. In a piano, a sounding board, a brace extending diagonally across a corner of said sounding board, said sounding board having slits at said corner whereby said corner is substantially free to vibrate.
3. In a musical instrument, a sounding board adapted to vibrate and reinforce the compressional waves, a portion of said sounding board being mounted in cantilever relationship and being free to vibrate independently of the remainder thereof.
4. In a piano, a sounding board adapted to propagate compressional waves, a frame supporting said sounding board, a portion of said sounding board being mounted in overhanging relationship with respect to said frame whereby said portion is substantially free to vibrate.
5. In a piano, a sounding board, means for supporting said sounding board in said piano whereby one corner of said sounding board is supported in cantilever relationship to the remainder thereof, and is free to vibrate at its extremities.
6. In a piano, a sounding board, means for supporting said sounding board on said piano, said sounding board having peripheral slots whereby portions of said board are disjoined from said support and are free to vibrate independently thereof.
7. In a piano, a sounding board having supports at its periphery, and having an additional support extending diagonally across said board, said board being free to vibrate on one side of said diagonal support and being restrained from vibration on the other side due to said peripheral support.
55. In testimony whereof I have herunto set my hand and seal.

JOHN HAYS HAMMOND, JR.
